United States Patent Office.

AMASA J. FINCH, OF NEW YORK, N. Y., ASSIGNOR TO MARGARET A. C. FINCH, OF SHELLSBURG, WISCONSIN.

Letters Patent No. 99,302, dated February 1, 1870.

IMPROVED PRINTERS' CHAIR.

The Schedule referred to in these Letters Patent and making part of the same.

To all whom it may concern:

Be it known that I, AMASA J. FINCH, of the city, county, and State of New York, have invented a new and useful Improvement in Printers' Chair; and I do hereby declare that the following is a full, clear, and exact description thereof, which will enable others skilled in the art to make and use the same, reference being had to the accompanying drawings, forming part of this specification.

Figure 1 is a side view of my improved chair.

Figure 2 is a detail rear view of the middle part of the same.

Similar letters of reference indicate corresponding parts.

My invention has for its object to furnish an improved chair for printers' use, which shall be so constructed as to allow the sitter to have as free a movement in every direction as when standing; and

It consists in the construction and combination of the various parts of the chair, as hereinafter more fully described.

A are the legs of the chair, which are connected by rounds in the ordinary manner.

Upon the lower ends of the legs A are cut spiral grooves, upon which are screwed the upper parts of the double-cone spiral springs B, the lower parts of which rest upon the floor, and which allow a side movement to the chair.

To the upper ends of the legs A is attached a board, C, in the centre of which is inserted a nut to receive the screw D, the upper end of which is attached to the cross-bar or board E, so that the seat of the chair may be raised and lowered, as desired.

F is the seat of the chair, which may be wood, cane, or upholstered, and which may be provided with a back, or not, as may be desired.

To the under side of the seat F, and to the upper side of the cross-bar or board E, are attached staples, through which is passed a rod, G, to hinge the seat F to the cross-bar or board E, which will allow the seat to have a free forward and backward movement.

The ends of the rod G are bent backward and upward, to form stops H, to prevent the seat F from rocking back too far.

I are coiled springs, one end of each of which is attached to the seat F, and the other ends are attached to the cross board E.

By this construction, the chair will allow movements, similar to the movements of the compositor's body when reaching for and picking up type.

Having thus described my invention,

I claim as new, and desire to secure by Letters Patent—

The printers' chair above described, so constructed that the sitter may turn and reach in all directions, consisting of spring I, hinge G, stops H, board E, screw D, seat F, support A C, and springs B, all arranged as set forth.

The above specification of my invention signed by me, this 3d day of September, 1869.

AMASA J. FINCH.
